UNITED STATES PATENT OFFICE.

WILLIAM C. HIERING, OF NEWARK, NEW JERSEY, ASSIGNOR TO J. E. MERGOTT CO., OF NEWARK, NEW JERSEY, A CORPORATION OF DELAWARE.

PERPETUAL CALENDAR.

Application filed July 3, 1926. Serial No. 120,274.

This invention relates to calendars and more particularly to types adapted to be disposed on desks and like flat surfaces in plain view of persons in the vicinity, such calendars being preferably combined with a base to be used as a paper weight, with or without a tray to contain miscellaneous small objects.

In calendars of this type the year is seldom shown, but the month, days of the week and days of the month appear, the days of the week remaining fixed while the month and days thereof require adjustment at the beginning of each month to properly co-ordinate.

The present invention has as its main object to provide a neat and attractively designed calendar frame appropriate as a desk ornament aside from the useful function of revealing the ordinary features of a common calendar.

Another purpose is in the provision of an easy and convenient means for shifting the scroll, bearing the numerals representing the days of the month, into proper relation to a fixed plate showing the names of the days of a week and having combined therewith efficient means for clamping the scroll in adjustment.

A further feature is to design a device that can be economically constructed from sheet metal, easily assembled and adjusted, and readily made use of as an advertising medium of unusual merit.

These several valuable features are attained by the novel construction and combination of parts hereinafter described and shown in the annexed drawing, constituting an essential part of this disclosure, and in which:—

Figure 1 is a front elevational view of a perpetual calendar made in accordance with the invention.

Figure 2 is an end elevational view of the same.

Figure 3 is an enlarged front view of the support frame and associated parts, the view being on line 3—3 of Figure 6.

Figure 4 is a longitudinal sectional view taken on line 4—4 of Figure 3.

Figure 5 is a similar view taken on line 5—5 of Figure 3.

Figure 6 is a transverse sectional view taken on line 6—6 of Figure 3.

Figure 7 is a fragmentary rear view showing the scroll adjusting means.

Figure 8 is a perspective view of the scroll engaging means.

Figure 9 is an enlarged fragmentary sectional view taken on line 9—9 of Figure 1 showing the frame construction.

Figure 10 is a fragmentary sectional view taken on line 10—10 of Figure 8, showing the scroll gripping means.

In the illustration the device is shown to consist of a generally oblong rectangular base 15 artistically die formed from sheet metal and having on its under side a sheet of felt 16 to avoid abrading the surface on which it may be placed.

The front portion of the base may be depressed to constitute a tray, not shown, and on the rear portion is fixed a rearwardly inclined bracket 17 engaging the lower member of a rectangular frame consisting of a front plate 18 having rearwardly reaching flanges 19 at each of its four sides, these flanges extending at right angles and having inwardly offset portions 20 containing small perforations 21.

The front plate 18 may be fancifully bordered as shown and its lower portion 18' is adapted to receive any desired impression, as an advertising device. A raised panel 22 on the upper part of the plate contains an elongated opening 23 through which is disclosed a strip of material 24, such as opaque white celluloid, bearing printed words representing the days of the week, as Sunday, Monday, etc.

Centrally above the opening 23 is a small opening 25 and in register below the opening 23 is a wider opening 26; a thin sheet 27 of transparent material such as mica or celluloid is fitted to the frame and disposed against the inner surface of the plate 18, rearward of the strip 24 and covering the openings 25 and 26 preventing the entrance of dirt to the interior.

Rearward of the transparent sheet 27 is a metal plate 28 of slightly lesser dimensions and having projections 29 turned rearwardly at right angles at each corner, acting to maintain the plate at the front as will later be seen.

A recess 30 extends downwardly from the upper edge of the plate 28 corresponding to the opening 25 in the face plate, and below

the recess 30 is a tubular boss 31 on which is rotatably mounted a disc 32, such as white opaque celluloid, bearing a circular row of spaced words designating the months of a year, as January, February, etc., the same showing through the recess 30, transparent sheet 27 and opening 25.

Registering radially with the words is an inner circular row of perforations 33, 10 equally spaced and equidistant from the center of the disc 32, which is held on the boss by spinning its tubular edge outwardly as best seen in Figure 4.

Engageable in any of the perforations 33 15 is a detent 34 formed near the end of a spring tongue 35 sheared from the material of the plate 28, this arrangement serving to retain the disc in adjusted position to disclose any selected month at the front of the 20 calendar, but permitting the extending edge of the disc to be manipulated in turning in either direction.

The main portion of the lateral edges of the plate 28, between the projections 29, 25 are curved to present hollow smoothly rounded guides 36, disposed in parallel closely adjacent the side flanges 19 of the frame, the inner edges of the guides being extended inwardly towards the center.

20 A scroll or strip 37, made of strong flexible material, as enamel coated muslin, is provided with lines dividing its outer surface into a plurality of squares on which are shown five rows of numerals, each row 35 containing numerals arranged to agree with the days of the month, this scroll extending interjacent the plate 28 and transparent sheet 27, and over the guides 36 to disclose the numerals through the opening 26.

40 The ends of the scroll 37 are held between pairs of clamps 38 formed by doubling sheet metal blanks upon themselves, the ends 39 of the blanks being wider than their central portions forming distinct 45 shoulders.

One of the sides of each clamp contains pairs of perforations 40 and the opposite sides are formed with spurs 41 which engage the fabric scroll ends and, in connection with the perforations 40, hold them in firm engagement when the clamp members are pinched together, as best seen in Figure 10.

55 A rear or cover plate 42 is formed with edge flanges 43 suited to engage neatly over the flange elements 20 of the front plate, the side flanges of the rear plate having inset prongs 44 to engage in the perforations 21 holding the structure firmly together.

60 A transverse slot 45 is formed centrally across nearly the entire width of the rear plate and guided by the slot is a slide 46 offset from a plate 47 having at its ends, 65 opposed lugs 48 adapted to extend past the edges of the paired clamps 38, closely against

their shoulders and be turned thereover, as best seen in Figure 8, binding the scroll carrying clamps and slide firmly together.

Fixed in the center of the slide 46 is a stem 49 formed on one side of a collar 50 disposed on the outer surface of the rear plate 42 and having an outwardly extending screw threaded stem 51 to which is fitted a thumb nut 52.

The nut 52 seats against a hollow washer 75 53 which upon setting up the nut binds the slide in adjusted position and, as will be clearly apparent, maintains the scroll in proper relation with the strip 24, in conformity with a standard calendar; it will 80 be noted that the collar 50 retains the slide within the slot at all times, irrespective of the nut, thus preventing disarrangement of the parts.

It will now be apparent that the months 85 may be changed by actuating the disc 32, and the first day of any month be brought to register with the proper day of the week by actuating the knob or nut 52, such changes 90 being required at the beginning of each month only.

Although I have described my improvements with considerable detail and with respect to certain particular forms of my invention, I do not desire to be limited to such details since many changes and modifications may be made without departing from the spirit and scope of my invention in its broadest aspect.

Having thus described my invention, what 100 I claim as new and desire to secure by Letters Patent, is:—

1. In a perpetual calendar, a casing having front and rear walls, a panel raised from the front wall bearing the days of the week, a scroll bearing the days of the month adjustable across an opening in the front wall, a guide for said scroll, means for actuating the scroll, a tubular boss on said guide, a disc rotatably mounted on said boss, said disc bearing the names of the months to appear through a recess in said front plate, the upper edge of said disc extending through the top of said casing to facilitate rotation, said disc having perforations corresponding to the names borne thereby, a spring tongue sheared from said guide, and a detent on said tongue engageable in any of the mentioned perforations whereby said disc is held in adjustment.

2. In a perpetual calendar, a casing having a front wall displaying the days of a week and an opening therebelow for the day of a month to appear, a scroll bearing numerals representing the day of a month, a guide for said scroll whereby it is held to view through the opening in said front plate, means to connect the ends of said scroll, a slide operable in a transverse slot 125 in the rear wall of said casing, means on 130

5 said slide to engage the scroll connecting means, a threaded stud on said slide extending outwardly through the slot, a collar fixed on said stud to retain the slide within the slot, a thumb nut on said stud, and a sleeve enveloping said collar interjacent said nut and rear wall to clamp said slide in an adjusted position.

10 3. In a perpetual calendar having a casting including front and rear plates, a guide loosely contained between said plates, said guide having curved lateral edges, a scroll bearing numerals representing days of the month disposed over said guide, said scroll being adjustable with respect to an opening in the front plate, a pair of opposed sheet metal clamps folded upon themselves to firmly engage the ends of said scroll, one of the elements of each clamp having perforations and the other element having projections to force the scroll material into the perforations, a slide movable in a slot in the rear plate, lugs on said slide to engage said clamps holding them tightly together, means 25 carried by said slide to facilitate adjustment of the clamped scroll, and means to secure said slide when adjusted.

4. In a perpetual calendar having a casting including front and rear plates, said

front plate having a view opening and said rear plate a transverse slot, a scroll bearing numerals visible through the opening, a guide for said scroll, clamps fixed on the ends of said scroll, a slide operable in the slot, means on said slide to hold said clamps in juxtaposition, means for shifting said scroll over the guide, means to clamp said slide in adjustment, and means to prevent displacement of said slide.

5. A perpetual calendar comprising a frame having a face plate containing openings through which the name of a month and numerals representing the days of the month may be seen, a panel intermediate the openings bearing the names of the days of the week, a rear plate in said frame having a transverse slot, a guide plate having curved lateral edges loosely confined in said frame, a scroll bearing numerals representing the days of a month, a slide movable in the slot of said rear plate, paired clamps operatively combined with said slide, means integral with said clamp to firmly engage the ends of said scroll, and means for clamping said slide in an adjusted position.

This specification signed this second day of July, 1926.

WILLIAM C. HIERING.
